PUMP

Edvin Ossian Parcival Thege, Stockholm, Sweden,
assignor to Aktiebolaget Atlas Diesel, Stockholm, Sweden, a corporation of Sweden

Application January 9, 1933, Serial No. 650,943
In Sweden July 11, 1932

6 Claims. (Cl. 103—41)

The present invention relates to pumps and has particular reference to adjustable fuel pumps for internal combustion engines of the solid injection type. The invention is particularly applicable to engines of the type in which governing is effected by varying the length of the effective discharge stroke of the pump and discharging superfluous fuel from the pump chamber through a pump release valve.

10 Broadly speaking, the general object of the invention may be said to be to improve upon prior forms of pump construction of the kind employing plunger actuated release valve structure. The manner in which this general object, and 15 other and more detailed objects and advantages of the invention which will hereafter be pointed out, are attained may best be understood by reference to the ensuing description of suitable forms of pump construction for carrying the invention 20 into effect.

In the accompanying drawings forming a part of this specification, Fig. 1 is a vertical transverse section through a fuel pump embodying the invention;

25 Fig. 2 is a transverse section taken on the line 2—2 of Fig. 1; and

Fig. 3 is a section similar to Fig. 1 showing another form of pump embodying the invention.

Referring now to the pump shown in Figs. 1 and 2, reference numeral 1 indicates a main frame or body of the pump. The pump shaft 2 is provided with a cam 3 acting on a lever 6 pivoted about a pin or shaft 4 and provided with a roller 5 for transmitting motion to the plunger element 35 of the pump. Roller 5 acts upon a tappet 7, reciprocably mounted in a guide 8 and restrained against rotational movement by a key 9 engaging a suitable key-way in the guide 8. The tappet 7 is forced downwardly by a spring 10 inserted 40 between a portion of the pump body and a flange 11 on the tappet. Spring 10 acts to cause the roller 5 and tappet 7 to follow the contour of the cam 3.

The upper portion of the tappet 7 is provided 45 with a recess having internal threads 12 engaged by external threads 13 on a plunger 14 reciprocable in a pump cylinder 15 inserted in the body of the pump and providing the working bore of the pump.

50 A gear 16 is mounted around the cylinder 15, the gear being rotatable with respect to the cylinder and fixed axially with respect to the cylinder. Two arms 17 attached to the gear project downwardly therefrom and pass respectively between two lateral projections 18 on the plunger

14. The arms 17 have relative axial movement with respect to the projections 18 and act to cause plunger 14 to rotate with gear 16 when the latter is turned. A rack 19 is reciprocably mounted in a transverse guide provided in the pump body and meshes with gear 16. Rack 19 is adapted to be shifted by an engine governor or other control means through suitable motion transmitting mechanism so that if the load on the engine is increased the governor rotates the gear 16, and with it the plunger 14, in a direction such that the compound plunger, formed by members 7 and 14, is shortened. Conversely, if the load on the engine is reduced, the length of the compound plunger is increased. 15

An annular member 50 is mounted in the pump body 1 above the pump cylinder 15 and the lower end of this member cooperates with the upper end of the pump cylinder to form the pump chamber 20 of the pump. The pump chamber 20 is placed in communication with an upper chamber 22 by means of channels including a series of passages 21 formed in and extending longitudinally through the member 50. Member 50 is retained in position by a part 51, recessed 25 to provide the upper chamber 22 and forming the seat for the spring loaded delivery valve 23. Fuel delivered to the chamber 22 on the working stroke of the pump flows past the delivery valve 23 to the outlet 24 adapted to be connected to 30 a device for injecting fuel to an engine cylinder.

The upper end of the bore of the annular member 50 provides a seat for the pump suction valve 25 which is urged toward closed position by the 35 valve spring 26. Fuel is supplied to the pump through the inlet conduit 27 in the pump body and passes therefrom through a series of transverse passages 28 extending laterally through the wall of the annular member 50. As will be observed from the drawings, these laterally extending passages provide communication between the fuel supply for the pump and the inlet side of the inlet valve.

In the embodiment illustrated, valve 25 is annular, having a central longitudinal bore in which is mounted the plunger portion of a release valve 29. The lower part of this plunger portion of the valve is tapered and engages a seat 30 formed in the lower portion of the annular member 50. 50 A part of the release valve 29, in the form of a pin, projects downwardly into the pump chamber 20 in a position to be contacted by the inner end of the plunger during its working stroke. The release valve is urged toward its seat by spring 31. 55

located in the upper chamber 22. A series of transverse passages 32 extending laterally through the side wall of member 50 above the valve seat 30 provide communication between the outlet side of the release valve and a channel 33 in the pump body which is in open communication with the fuel supply.

The operation of the pump is as follows. During the suction stroke of the plunger under the influence of spring 10, fuel is drawn into the pump chamber 20 from the supply conduit 27, through the transverse passages 28, valve 25 and the longitudinally extending passages 21 in the member 50. On the return or working stroke, effected by the action of the cam 3, the plunger forces fuel from the chamber 20 through the passages 21, past the closed suction valve 25, and into the upper chamber 22. The fuel further flows through the delivery valve 23 and the outlet 24 to the fuel injection device of the engine. Before reaching the end of its working or discharge stroke, the plunger 14 strikes the pin projecting into the pump chamber to open the release valve 29. After the release valve is opened, the superfluous fuel displaced by further movement of the pump plunger during the latter part of its discharge stroke, is returned to the fuel supply by way of the transverse passages 32 in the member 50.

30 The opening of the release valve may be said to determine the end of the effective discharge stroke of the pump and the time at which liquid is released from the pump chamber to terminate the effective discharge stroke is varied by altering the length of the compound pump plunger formed by the parts 7 and 14. Alteration of the length of the pump plunger is accomplished by movement of rack 19 and consequent rotation of the gear 16. Movement of the gear turns the plunger part 14 to a higher or lower position in the tappet 7 and consequently causes the inner end of the plunger 14 to open the release valve at an earlier or later time, as the case may be, in the cycle of operation of the pump. Earlier opening of the release valve results in less fuel being supplied per working stroke of the pump and later opening of the release valve results in a greater quantity of fuel being supplied per working stroke.

In order to reduce the shock of contact between the plunger and the release valve pin, the upper end of the plunger may advantageously be provided with a cavity 34 which is filled with liquid which must be displaced as the two parts come into contact.

The high liquid pressure existing in the pump chamber during the discharge stroke of the pump and reacting against the inner end of the plunger 14, tends to cause the plunger to turn with respect to the tappet 7 in a direction shortening the length of the compound plunger. This tendency of the plunger to turn under the influence of pressure from the pump chamber would, if not counteracted, place an undesirable load on the governor mechanism connected to the rack 19. Even if the threads 12 and 13 are of a pitch so as to be self-locking, different amounts of force would be required to shorten or elongate the compound plunger, since if the governor acted to elongate the plunger during the working stroke of the pump, sufficient force would have to be applied to the rack 19 to screw the plunger 14 upwardly against pump chamber pressure while such force would not be required if the governor

acted to screw the plunger 14 downwardly to shorten the length of the pump plunger.

In order to substantially eliminate the influence of pump chamber pressure on the governing means, the lower portion of the plunger 14 is advantageously made hollow and a closely fitting plug or piston 35 is mounted therein with its lower end resting on the bottom of the recess in the tappet 7. A spring 36 above the plug 35 serves to hold the latter in contact with the tappet 7. A channel 37, passing through the plunger 14, provides communication between the chamber in the lower end of the plunger 14 and the pump chamber 20. As will be observed from the drawings, the cross sectional area of this lower chamber is substantially equal to the cross sectional area of the end of the plunger 14 which is exposed to pump chamber pressure and, it will be evident from this that during the working stroke of the pump, the plunger 14 will be substantially balanced against end pressure imposed by the pressure of liquid in the pump chamber. Consequently, the position of plunger 14 relative to the tappet 7 may be shifted by the application of very little force to the rack 19.

25 The balancing feature of the pump plunger construction hereinabove described is not per se a part of the present invention and forms the claimed subject matter of U. S. Patent 1,989,720, granted February 5, 1935, on an application filed by me January 9, 1933.

Referring now to Fig. 3, the construction of the form of pump shown therein is in general the same as that previously described in connection with Fig. 1. In the present form of construction however, a combined suction and release valve is provided comprising a valve head 38 having a plunger like extension fitting in the bore of the annular member 50a and projecting into the pump chamber to be contacted by the end of the 35 pump plunger 14. As in the embodiment shown in Fig. 1, the pump member 50a is provided with a series of longitudinally extending passages 21 providing communication between the pump chamber 20 and the upper chamber 22, the latter being in communication with the delivery valve 23 and outlet passage 24. The fuel supply channel 21 is placed in communication with the inlet side of the suction valve 38 by means of a series of transverse passages 28 extending through 50 the side wall of the annular member 50a and passages 32a are also formed in member 50a, the latter passages providing communication with the inlet side of the suction valve and the liquid supply passage 33 in the pump body. In other respects, the construction is as previously described.

55 On the suction stroke of the pump, fuel is drawn from the channels 27 and 33 through passages 28 and 32a, through the suction valve and passages 21 to the pump chamber. On the discharge stroke of the pump, fuel is forced from the pump chamber 20 through channels 21 past the closed suction valve to the chamber 22 from which it passes through the delivery valve to the outlet channel 24. The effective discharge stroke 60 is terminated by contact of the inner end of the plunger 14 with the part 39 of the suction valve which now acts as a release valve to permit excess liquid displaced by the pump plunger to flow back to the liquid supply through the passages 28 and 32a.

65 By constructing the pump in the manner hereinbefore described, numerous practical advantages of considerable importance are obtained. By arranging the suction and release valve struc-

ture and the necessary suction, discharge and release valve passages in a separate pump member, and further, by providing a separate pump cylinder, it is possible to make the pump body 5 of cast material of relatively low strength and to relieve the body of the extremely high pressures developed in a fuel injection pump. The construction lends itself to accurate and relatively inexpensive manufacture of those parts of the 10 pump structure which require accuracy of dimensions and since such parts may be made separately of material suitable for withstanding the high pressures encountered, it will be evident that the cost of manufacture of the pump may be very 15 considerably reduced as compared with a form of construction which would require all or a part of the pump body to be exposed to pressures necessitating the use of wrought or other high tensile strength material to resist them.

20 It will be evident to those skilled in the art that the invention is not limited to the specific forms of construction disclosed herein by way of example and it is to be understood that the invention embraces all forms of apparatus falling 25 within the scope of the appended claims.

I claim:

1. In a reciprocating pump having a working bore, a pump body, means providing a pump chamber at one end of said bore including a 30 member mounted in said body, a pump plunger working in said bore, valve means mounted in said member for admitting liquid to said chamber and for releasing liquid therefrom including a part arranged to be contacted by one end of the plunger on its discharge stroke to effect release of liquid from said chamber, and a pump delivery valve, said member having passages formed therein for placing said valve means in communication with the pump chamber and with 40 the liquid supply for the pump and for placing the pump chamber in communication with the pump delivery valve.

2. In a reciprocating pump having a working bore, a pump body, means providing a pump chamber at one end of said bore including a 45 member mounted in said body, a pump plunger working in said bore, a combined suction and release valve mounted in said member, said valve including a part arranged to be contacted by one end of the pump plunger on its discharge stroke to effect release of fuel from said chamber, and a pump delivery valve, said member having 50 passages formed therein for placing the pump chamber in communication with the outlet side of said suction and release valve and with the inlet side of said delivery valve and for placing the inlet side of said suction and release valve in communication with the liquid supply for the pump.

3. In a reciprocating pump having a working bore, a pump body, means providing a pump chamber at one end of said bore including a 55 member mounted in said body, a pump plunger working in said bore, a pump suction valve mounted in said member, a pump release valve mounted in said member and having a part arranged to be contacted by one end of the plunger on its discharge stroke to effect release of liquid

from the pump chamber, and a pump delivery valve, said member having passages formed therein for placing the pump chamber in communication with the outlet side of the suction valve and with the inlet sides of the delivery valve and of the release valve and for placing the inlet side of the suction valve and the outlet side of the release valve in communication with the liquid supply for the pump.

4. In a reciprocating pump, a pump body, a 10 cylinder mounted in said body providing a working bore, a member mounted in said body in alignment with said cylinder at one end thereof and cooperating therewith to form a pump chamber, a pump plunger working in said bore, 15 valve means mounted in said member for admitting liquid to said chamber and for releasing liquid therefrom including a part arranged to be contacted by one end of the plunger on its discharge stroke to effect release of liquid from said 20 chamber, and a pump delivery valve, said member having passages formed therein for placing said valve means in communication with the pump chamber and with the liquid supply for the pump and for placing the pump chamber in 25 communication with the pump delivery valve.

5. In a reciprocating pump, a pump body, a cylinder mounted in said body providing a working bore, an annular member mounted in said body in alignment with said cylinder at one end thereof and cooperating therewith to provide a pump chamber, suction and release valve means mounted in said member including a part extending centrally therethrough to be contacted by one 30 end of the pump plunger on its discharge stroke 35 for effecting release of liquid from the pump chamber, a pump delivery valve, passages extending longitudinally through said member for flow of liquid from said valve means to the pump chamber on the suction stroke of the pump and 40 for flow of liquid from the pump chamber to the delivery valve on the working stroke of the pump, and transverse passages extending laterally through the wall of said member between the longitudinally extending passages for flow of liquid 45 from the liquid supply to the inlet side of said valve means and for return flow of excess liquid from the pump chamber to said supply.

6. In a reciprocating pump having a working bore, a pump body, means providing a pump 50 chamber at one end of said bore including a member mounted in said body, a compound pump plunger working in said bore, valve means mounted in said member for admitting liquid to said chamber and for releasing liquid therefrom including a part arranged to be contacted by one 55 end of the plunger on its discharge stroke to effect release of liquid from said chamber, a pump delivery valve, said member having passages formed therein for placing said valve means in 60 communication with the pump chamber and with the liquid supply for the pump and for placing the pump chamber in communication with the pump delivery valve, and means for altering the length of said pump plunger to vary the time of 65 release of liquid from the pump chamber.

EDVIN OSSIAN PARCIVAL THEGE.
